(57) **CLAIM**

The ornamental design of a microphone, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front elevational view of a microphone.
FIG. 2 is a bottom, rear perspective view thereof;
FIG. 3 is a bottom plan view thereof;
FIG. 4 is a right-side elevational view thereof;
FIG. 5 is a rear elevational view thereof;
FIG. 6 is a top plan view thereof; and,
FIG. 7 is a rear perspective view thereof.

1 Claim, 7 Drawing Sheets
